PISTON RING ARBOR

Holly M. Olson, Muskegon, Mich., assignor to
 Sealed Power Corporation, Muskegon, Mich., a
 corporation of Michigan

Application April 1, 1946, Serial No. 658,817

7 Claims. (Cl. 279—2)

1

The present invention relates to a novel construction of arbor, designed primarily for the releasable holding of piston ring castings, the arbor being rotated and a plurality of spaced rotatable saws brought to the piston rings at their outer curved surfaces and between their opposed flat sides to split or divide the castings preferably into two ring castings from each of which a piston ring is made.

It is an object and purpose of the present invention to provide an arbor of the character noted, having ring casting and engaging jaws adapted to be forced outwardly radially to engage the ring castings at their inner curved sides and hold them securely against movement with respect to the arbor. As the ring castings are not of circular form, but of an out-of-round character, means are provided for expanding or forcing the jaws outwardly to properly engage the ring castings at their inner curved sides at spaced distances with a yielding pressure, and use a means which is not damaged, and in time, destroyed to the extent that it needs frequent replacement, as in some prior arbors devised for such ring casting splitting or sawing.

An understanding of the invention may be had from the following description taken in connection with the accompanying drawing in which,

Fig. 1 is a plan view of the arbor and cooperating saws.

Fig. 2 is an elevation thereof, the ring castings to be divided being shown in section.

Fig. 3 is a horizontal section through the arbor substantially on the plane of line 3—3 of Fig. 4.

Fig. 4 is a vertical section through the arbor and its mounting.

Fig. 5 is a fragmentary side elevation looking against Fig. 4 from the left.

Fig. 6 is a perspective view of a preferred resilient spring member, one of which is used back of each series of vertical ring casting engaging jaws and,

Fig. 7 is a perspective view illustrating a modified form of spring actuating jaw member.

Like reference characters refer to like parts in the different figures of the drawings.

The arbor which I have designed is adapted to be used in a vertical position and turn about a vertical axis, though it can be as well used when turned about a horizontal axis. Within a fixed housing 1, a driven vertical spindle 2 is mounted for rotation having an enlarged head 3, recessed at its upper end and interiorly threaded for the screw connection of the lower end of the arbor body 4, as shown in Fig. 4.

2

The spindle 2 is hollow lengthwise thereof and the arbor body 4 is similarly hollow in the direction of its length, the interior cylindrical passage in the arbor being of a larger diameter than that in the spindle 2. A cylindrical member 5 is mounted for longitudinal movement within the arbor body 4. It is radially slotted from its outer sides inwardly, the construction shown having six slots 6 (Fig. 3) equally spaced from each other. The greatest depth of each slot is at its upper end portion and at its lower portion the bottom of each slot is inclined downwardly and outwardly as indicated at 7 (Fig. 4).

A headed rod 8 passes through an axial passage 15 in the member 5 and has screw connection to a rod 9 which extends through the spindle 2 and may be longitudinally operated to move the member 5 upwardly or downwardly in accordance with the direction of movement of the rod 9.

20 In each of the slots 6 an inwardly extending wedge shaped rib 10, integral at its outer portions with a vertical transverse head 11 is located, the inner edge of each rib 10 having the same inclination as the lower portion of the bottom of the slot 7 in which it is located. Thus when the member 5 is moved upwardly, the ribs 10 with their heads 11 are simultaneously moved equal distances radially outward.

At the outer side of each head 11 and midway 30 between its vertical edge an elongated vertical rib 12 is formed. It bears against the center of a resilient member 13 made from a plate of spring material and formed, as shown in Fig. 6 at each vertical side edge with a plurality of 35 consecutive spring fingers 14.

It is to be understood that the body 4 of the arbor is provided with vertical slot openings extending from its outer sides radially inward, there being the same number of such openings 40 as there are slots 6 in the member 5, and that the heads 11 and the resilient members 13 have a width such that they fit said slots and are freely movable therein.

At the outside of each of the resilient members 45 13 a plurality of jaws 15 are located in a superimposed relation. There is thus provided around the arbor a plurality of series of jaws, six of said jaws in each series, each of the series located in a horizontal plane. Each of the series of jaws 50 is adapted to engage the inner curved side of a double width piston ring casting, and said jaws at their outer edges are formed with serrations or teeth to provide firm engagement. Each of the jaws is vertically slotted between its side edges and also horizontally slotted from its outer

edges inwardly for a distance for purposes which will hereinafter appear.

The vertical stacks of jaws, there being six of such stacks in the disclosure made, are each mounted between upper and lower guiding members or bushings 16 and 17 (Fig. 4) held by screws, the upper member 16 being flattened on its lower side and the lower member 17 flattened at its upper side. The guiding bushings 16 and 17 are axially bored for the reception of coiled tension springs 18 which are connected at their outer ends to the upper and lower ends of a vertical bar 19 which is located in the alined vertical grooves of the jaw members 15. The inner ends of the springs 18 are anchored at the bottoms of the bushings 16 and 17, said jaws being thus yieldingly pressed against the fingers 14 of the resilient member 13. At the upper end of the arbor body a releasable covering cap 20 with spring latches 21 is used to cover the upper end of the arbor and exclude dirt or other foreign matter.

With the rod 9 and the expanding member 5 lowered to a position below that in Fig. 4, the several springs 18 will withdraw the engaging jaws 15 radially inward, and a plurality of double ring castings 22 may then be placed over the arbor, the lowermost casting rest upon the upper sides of the outer end portions of the bushings 17. After placing the required number of the ring castings 22 to the height of the uppermost jaws 15, the rod 9 is moved longitudinally in an upward direction forcing the heads 11 out by a wedging action of the ribs 10 against the inclined bottoms 7 of slots 6, and all of the jaws will be simultaneously moved radially upward, stretching the springs 18 and pressing the serrated outer edge portions of jaws 15 against the inner sides of the castings 22, thus securely holding the ring castings in fixed relation to the arbor. It is of course to be understood that the thickness of the jaws 15 is the same as the thickness of a double width ring casting 22.

As thus held, the arbor and the ring castings thereon may be rapidly turned by driving the spindle 2. The ring castings are sawed through between their upper and lower sides by a proper number of circular metal saws 24, one for each casting, mounted on a carrying head 23 connected and rotatable with a vertical driven shaft which is mounted so that the saws may be moved toward and away from the castings, the detail of which need not be described. The saws and rings, both rotating about parallel vertical axes, in the vertical stack of ring castings all of the castings are simultaneously divided into two ring castings, from each of which the piston ring is produced.

In such outward movement of all of the jaws simultaneously the spring fingers 14 yield as much as may be necessary, some more than others, so that all jaws at their outer serrated edges have the desired holding engagement thereof with the inner surfaces of the ring castings with which they engage. The horizontal grooves at the outer faces of the jaws 15 provide spaces into which the saw teeth may enter when breaking through at the inner sides of the castings.

In Fig. 7 there is shown, for the head 11 and the resilient member 13 with its opposite spring fingers 14, a substitute in the form of a bar 25 of the same length but rectangular in cross section, in the outer face of which two vertical rows of coiled springs 26 are mounted as shown, said springs at their outer ends bearing against the

inner ends of the jaws 15. This provides an equivalent construction with that previously described for a yielding spring pressure against the jaws when they are forced outwardly to engage the ring castings.

After the ring castings have been simultaneously split or divided into two parts, rod 9 is moved downward to release the jaws, and the divided castings may be removed and a new vertical stack of castings put on the arbor and the operation repeated. The holding and sawing of the double width castings is very expeditiously and otherwise satisfactorily attained. While the arbor is used in connection with a vertical spindle and for some reasons such vertical position is preferred, the arbor may be used mounted to turn about a horizontal axis with the saws driven about a parallel axis. Further, while the disclosure has been made with respect to holding 10 double width castings, each of which is sawed into two parts, the arbor may also be used for holding castings of greater widths, sawed or divided into more than two parts, or for holding cast sleeves having a length equal to the combined widths of 15 the plurality of double width ring castings disclosed, and said sleeves sawed by the saws 24 into a large number of parts from each of which a piston ring may be made. The invention, therefore, is not to be limited to vertical arbors nor 20 to sawing double width ring castings only, but is comprehensive of all forms of structure coming within the scope of the appended claims which define the invention.

I claim:

35. 1. An arbor comprising, a body adaptably mounted for rotation about its longitudinal axis, said body having a plurality of spaced longitudinal openings in its sides, said openings being elongated in the direction of the length 40 of the body and said body having an axial passage therethrough, an actuating member mounted for reciprocable movement within said passage, said actuating member having a plurality of inclined faces, one in opposition to each of 45 said openings through the body; means for moving said actuating member selectively in either direction, and radially positioned expanding members located one in each opening and at its inner side having an inclined face to bear against an associated inclined face on the actuating member, a plurality of ring casting engaging jaws disposed in side by side relation to each other at each of the openings in the body, yielding means between each of said plurality of jaws and the outer side of each of said radially expanding members, and yielding means acting on said jaws to normally press them inwardly.

2. A construction as defined in claim 1, each of said plurality of jaws being recessed in alinement at their outer portions, a bar located in the alined recesses of each of said plurality of jaws and tension springs connected to the ends of said bars and to said body, as specified.

3. A construction as defined in claim 1, each of 65 said jaws being grooved at its outer portions substantially midway between its opposite sides, the outer edges of said jaws at sides of the grooves being serrated to provide a plurality of teeth to engage against the inner side of a piston ring casting.

4. An arbor as described comprising a substantially cylindrical body having a cylindrical longitudinal opening or passage therethrough, said body at a plurality of spaced positions 75 around it having openings radially therethrough,

said openings being elongated in the direction of the length of the body, hollow guides permanently secured one at each end of each of said openings, springs housed one in each of said guides and connected at their inner ends thereto, a bar extending between the guides at each of said openings to the ends of which said springs are connected, a plurality of jaws mounted side by side between the guides at each of said openings, said bars bearing upon the outer portions of the jaws to tend to move them inwardly, an actuating cylindrical member mounted for longitudinal movement in the longitudinal passage through said body, said cylindrical member having a plurality of radial slots lengthwise thereof one for each opening, the bottoms of said slots having a portion of the length thereof disposed at acute angles to the axis of the actuating member, a radially movable expansion member located at its outer portion in each of said body openings and having a portion extending into a slot in the actuating member, the inner edge of which is disposed at the same angle as the bottom of the slot in which it is received, and yielding spring means between the inner edges of said jaws and the outer side of each of said radial expanding members.

5. A construction as defined in claim 4, and means connected with said actuating member for selectively moving it in either direction in the

direction of its length, said spring means between the jaws and the radially expanding members comprising each a flat plate of spring material notched at its opposite edges to provide oppositely extending yielding spring fingers, two of which fingers engage at the back of each of said jaws.

6. A ring casting holding arbor comprising, a cylindrical body adapted to be mounted for rotation about its longitudinal axis, a plurality of spaced series of jaws carried by said body therearound, each of said series of jaws comprising a number of the jaws located in side by side relationship, means for forcing all of the jaws radially outward simultaneously, spring means operatively connected with each of the series of jaws for normally moving them radially inward, and individual spring means at the inner sides of each of said series of jaws yieldable to permit all of the series of jaws to engage the inner curved sides of out-of-round piston ring castings disposed around said arbor at the outer ends of the jaws.
7. A construction as defined in claim 6, each of said jaws at its outer edge portion between opposite sides being grooved and the outer portions of each of said jaws at each side of the groove having teeth for the purposes described.

HOLLY M. OLSON.
